RADIO CABINET

Kurt Emde, Itasca, and Herbert H. Steglich,
Wilmette, Ill., assignors to Zenith Radio Cor-
poration, a corporation of Illinois

Application December 15, 1947, Serial No. 143,159

Term of patent 7 years

(Cl. D56—4)

To all whom it may concern:

Be it known that we, Kurt Emde and Herbert H. Steglich, citizens of the United States and residents, respectively, of Itasca, in the county of DuPage, State of Illinois, and of Wilmette, in the county of Cook, State of Illinois, respectively, have invented a new, original, and ornamental Design for a Radio Cabinet, of which the following is a specification, reference being made to the accompanying drawings, forming a part thereof.

Figure 1 is a front view of a radio cabinet, showing our new design;

Figure 2 is a front perspective view of the radio cabinet;

Figure 3 is a sectional view taken along lines 3—3 of Fig. 1 and;

Figure 4 is a sectional view taken along lines 4—4 of Fig. 1.

Figure 5 is a sectional view taken along lines 5—5 of Fig. 2.

The other side of the cabinet is the same as the side shown and the rear is plain.

We claim:

The ornamental design for a radio cabinet, as shown and described.

KURT EMDE.
HERBERT H. STEGLICH.
